US00D914331S

(12) United States Design Patent (10) Patent No.: US D914,331 S
(45) Date of Patent: * Mar. 30, 2021

(54) WEARABLE PONCHO WITH NECK
WARMER

(71) Applicant: Nelson Yan, Los Angeles, CA (US)

(72) Inventor: Nelson Yan, Los Angeles, CA (US)

() Term: 15 Years

(21) Appl. No.: 29/725,508

(22) Filed: Feb. 25, 2020

(51) LOC (13) Cl. 02-02

(52) U.S. Cl.

USPC D2/724

(58) Field of Classification Search

USPC D2/831, 823, 719, 724; D6/603

CPC A41D 27/00

(57) CLAIM

The ornamental design for a wearable poncho with neck warmer, as shown and described herein.

DESCRIPTION

FIG. 1 is a front elevation view of the wearable poncho with neck warmer, showing my new design, with the hood up; FIG. 2 is a rear elevation view thereof; FIG. 3 is a left side elevation view thereof; FIG. 4 is a right side elevation view thereof; FIG. 5 is a bottom plan view thereof; and FIG. 6 is a top elevation view thereof; and FIG. 7 is a front elevation view of the wearable poncho with neck warmer, showing my new design, with the hood rolled down; FIG. 8 is a rear elevation view thereof; FIG. 9 is a left side elevation view thereof; FIG. 10 is a right side elevation view thereof; FIG. 11 is a bottom plan view thereof; and FIG. 12 is a top plan view thereof. The broken lines are for environmental purposes only and form no part of the claimed design.

1 Claim, 8 Drawing Sheets
